(57) **CLAIM**

The ornamental design for a sleep mask with pocket, as shown and described.

DESCRIPTION

FIG. 1 is a perspective view showing an exemplary embodiment of our new sleep mask with pocket design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof; and,

FIG. 8 is a perspective view of an exemplary embodiment of the present design removably engaged about a user's head. It should be noted that, pursuant to 37 C.F.R. § 1.152 and MPEP § 1503.02, Part III, broken, dashed, or phantom lines have been used throughout the drawings to illustrate inherent but unclaimed features of our sleep mask with pocket design, which features are expressly not claimed as part of said design, are shown strictly for context, and are unrelated to any indication of the relative importance of such features.
